UMBRELLA CAP AND COVER

Heinz Weber, Hilden, Germany, assignor to Telesco Brophy Limited, Montreal, Quebec, Canada

Continuation-in-part of design application Ser. No. 20,258, Nov. 24, 1969. This application July 29, 1970, Ser. No. 24,206

Claims priority, application Germany Sept. 5, 1969

Term of patent 14 years

Int. Cl. D3—03

U.S. Cl. D88—3

FIG. 1 is a perspective view of an umbrella showing my new design, the frame structure being conventional;

FIG. 2 is an enlarged fragmentary perspective view of the central portions of FIG. 1;

FIG. 3 is a further enlarged top plan view of FIG. 2;

FIG. 4 is a side elevational view of FIG. 3 as taken from lines 4—4; and

FIG. 5 is an end elevational view of FIG. 3 as taken from lines 5—5.

The characteristic feature of my design resides in the particular shape of the cap portion in combination with the cover portion, all as shown.

This application is a continuation-in-part of applicant's copending application Ser. No. D. 20,258; filed Nov. 24, 1969, entitled "Umbrella Cap", now abandoned.

I claim:

Ornamental design for an umbrella cap and cover, as shown and described.
